UNITED STATES PATENT OFFICE.

EMILE MERTZ, OF BASEL, SWITZERLAND.

MULTISTAGE TURBINE.

No. 892,440.

Specification of Letters Patent.

Patented July 7, 1908.

Application filed September 10, 1906. Serial No. 334,056.

To all whom it may concern:

Be it known that I, EMILE MERTZ, citizen of Switzerland, residing at Basel, Switzerland, have invented new and useful Improvements in Multistage Impulse-Turbines for Elastic Motive Fluids Under Pressure, of which the following is a specification.

My invention relates to multi-stage impulse turbines for elastic motive fluids under pressure and has for its object to constructional improve and render such turbines more efficient in action. I attain these objects by the mechanism illustrated in the accompanying drawing, in which—

Figure 1 is part of a longitudinal section of a turbine constructed in accordance with one embodiment of my invention. Fig. 2 a portion of the evolution of a cylindrical section on line A—B Fig. 1. Fig. 3 partly a side view and partly a longitudinal section on an enlarged scale showing the manner of securing the blades to the moving wheels. Figs. 4 and 5 are respectively sections on lines C—D and E—F of Fig. 3. Fig. 6 is a longitudinal section showing another embodiment of my invention. Figs. 7 and 8 are respectively a longitudinal and an evolved cylindrical section on an enlarged scale of blades constructed in accordance with a further embodiment of my invention.

Similar letters refer to similar parts throughout the several views.

Referring to Fig. 1, 1 is the inlet and 2 the outlet for the motive fluid. The expansion guide wheels 3 are rigid in the turbine casting, while the moving wheels 4 which alternate therewith are secured to the shaft 28. The wheels 3 and 4 are divided into groups 5, 6, 7 and 8 along the shaft 28.

As will be seen from Fig. 2, the length of impact peripherically, that is to say, the length of the arc of impact is the same in all the moving wheels of one group, but increases from group to group towards the exhaust, so that the groups 5—8 (Fig. 2) have the increasing lengths 9—12.

The cross section of the channel of the guide wheels 3, that is to say, the distance between the guide blades, is the same in all the groups. The motive fluid crosses from one group to the other through the channels 13, 14 and 15, the cross section of which is limited as required to prevent a detrimental expansion of the stream of fluid between the groups. The height of the blades of the guide wheels 3 and the moving wheels 4 in-

creases in each group from wheel to wheel, in such a manner that the blades of the first wheel of all the groups have the same minimum and the blades of the last wheel of all the groups the same maximum height.

The moving wheels consist each of a plain disk 16, Figs. 1 and 3—5, having equi-distant holes in its periphery adapted to receive the studs 19 of the blades 18. These blades are rigidly secured to the disks 16 by means of rivets 20 passing between the studs 19 through cross holes in the disk 16 and segmental recess in the sides of the studs. A hoop 21 shrunk over the outer ends of the blades 18 prevents vibration of the blades.

The blade apertures in the guide wheels 3 have each a pocket like recess *a* situated at the side adjacent to the preceding moving wheel and at the end facing the direction in which the latter rotates.

The stream of fluid which owing to the absolute path is diverted from the generatrix of the impact cylinder in passing between the moving wheel blades, is always completely caught by the said pockets and guided back into the said generatrix before entering the next moving wheel, whereby in an even number of multiple impact of moving wheels and with guide wheels made in halves to facilitate erection, an almost complete impact is obtained in the last group without the necessity of the blade apertures of the said guide wheels having to intersect the joints of the latter.

The blades of the guide wheels 3 are the distance necessary for the passage of the fluid apart from the blades of the preceding moving wheel, so that the motive fluid distributes itself in the whole of the aperture and will pass equally through all the guide cells of the aperture and also that the play between the wheels at a point where the motive fluid does not pass is reduced to a minimum.

In the embodiment shown in Fig. 1, the wheels of the same class are the same diameter in all the groups, while in the embodiment shown in Fig. 6 the diameter of the wheels of the same class increases from group to group.

In lieu of giving the channels of the guide-wheels of each group the same breadth and to increase the height of the blades from one pair of wheels to the other, as shown in Figs. 1, 2 and 6, the height of all wheels of one group may be the same and the breadth,

that is to say, the section of the guide wheel channels increased, as shown in Figs. 7 and 8. In the latter case the angle $\alpha - \alpha_5$ at which the motive fluid enters the moving wheels, increases from one pair of wheels to the other, by which means the length of impact remains the same.

It is obvious that according to the number of horse-power and the pressure at which the motive fluid is used, the turbine may have only two or more than four groups of wheels, the number of wheels in each group may also vary, for instance, it may be large in the first group and then decrease from group to group.

The improvements described reduce the loss of power caused by the whirling of the motive fluid and friction of the wheels considerably and an almost complete ideal friction-less passage of the stream of motive power is obtained in the turbine, as the velocity of the motive power in passing from the moving wheels to the stationary wheels is as much as possible utilized and the stream of motive power in passing from wheel step to step and wheel group to group does not unnecessarily spread out or expand.

The number of wheels required in comparison with the power obtained in my improved turbine are also less than hitherto consequently it will be less in size and require less room.

I claim:

1. In a multi-stage elastic fluid pressure turbine with partial impact, the combination with pressure stages arranged in groups and with arcs of impact having the same or approximately the same peripheral impact, increasing from group to group towards the

turbine exhaust, of fluid guide channels between the said groups, the section of which is limited to the required extent, substantially as and for the purpose set forth. 40

2. In a multi-stage elastic fluid pressure turbine with partial impact, the combination with pressure stages arranged in groups and with arcs of impact having the same or approximately the same peripheral impact, increasing from group to group towards the turbine exhaust, of fluid guide channels between the said groups, the section of which is limited to the required extent, guide wheels and moving wheels and blade apertures in the said guide wheels each of which has a pocket-like recess situated at the side adjacent to the preceding moving wheel and at the end facing the direction in which the latter rotates, substantially as and for the purpose set forth. 50

3. In a multi-stage elastic fluid pressure turbine with partial impact, the combination with moving wheels with radial holes in their periphery, of blades having each a stud at its inner end with a segmental recess across its side, cross holes in the moving wheels between each two of the said radial holes corresponding with the said recesses and means in the said cross holes engaging in the said recesses, substantially as and for the purpose set forth. 60

In testimony whereof I have signed my name to this specification in the presence of two subscribing witnesses. 70

EMILE MERTZ.

ANDREW HEER.

DISCLAIMER.

892,440.—*Emile Mertz*, Basel, Switzerland. MULTISTAGE TURBINE. Patent dated July 7, 1908. Disclaimer filed March 27, 1909

Enters this disclaimer—

“To that part of the claim in said specification which is in the following words, to wit:

“As will be seen from Fig. 2, the length of impact peripherically, that is to say, the length of the arc of impact is the same in all the moving wheels of one group, but increases from group to group toward the exhaust, so that the groups 5—8 (Fig. 2) have the increasing lengths 9—12.” (Page 1, lines 40—46.)

“The height of the blades of the guide wheels 3 and the moving wheels 4 increases in each group from wheel to wheel, in such a manner that the blades of the first wheel of all the group have the same minimum and the blades of the last wheel of all the groups the same maximum height.” (Page 1, lines 55—61.)

“In lieu of giving the channels of the guide-wheels of each group the same breadth and to increase the height of the blades from one pair of wheels to the other, as shown in Figs. 1, 2 and 6, the height of all wheels of one group may be the same and the breadth, that is to say, the section of the guide wheel channels increased, as shown in Figs. 7 and 8. In the latter case the angle ≈ 5 at which the motive fluid enters the moving wheels, increases from one pair of wheels to the other, by which means the length of impact remains the same.” (Lines 107—112, page 1, and lines 1—7, page 2.) “and with arcs of impact having the same or approximately the same peripheral impact, increasing from group to group toward the turbine-exhaust;” (Page 2, lines 37—40.)

“and with arcs of impact having the same or approximately the same peripheral impact, increasing from group to group towards the turbine exhaust;” (Lines 47—50, page 2.)

“fluid guide channels between the said groups, the section of which is limited to the required extent.” (Lines 50—52, page 2.) [Official Gazette, April 6, 1909.]
